BOX LINING FORMING AND INSERTING MACHINE

Emil G. Jurgens, Chicago, and Hazen K. Becker,
Winnetka, Ill., assignors to Peters Machinery
Co., Chicago, Ill., a corporation of Illinois

Application September 14, 1940, Serial No. 356,774

3 Claims. (Cl. 93—36.01)

The improvements herein specified relate to machines for forming box linings, placing the linings in boxes and removing the lined boxes from the machine. Such machines generally include a continuous conveyor carrying a series of forms which engage lining sheets and carry the sheets while the latter are being mechanically folded around the forms to bag shape. The linings may be fitted in boxes during the folding operation, after which operation the lined boxes are ejected from the machine.

The improvements are directed to the particular mechanism employed for folding the lining sheets around the forms; to an arrangement for inserting the linings into boxes; and to a specific ejecting mechanism for the lined boxes.

A specific construction embodying the improvement is illustrated by the accompanying drawings, wherein:

Figure 1 is a longitudinal sectional view of a box lining machine employing the improvements.

Figs. 2 through 7 are fragmentary enlarged details in side elevation and partly in section, illustrating successive operations on the lining material.

Figs. 8 through 11 are fragmentary details in side elevation partly in section, and on a larger scale than Figs. 2 to 7, inclusive, illustrating continued folding operations.

Fig. 12 is an enlarged detail partly in section, showing in side elevation the construction of a flap folding device.

Fig. 13 is a front view of the mechanism shown in Fig. 12.

Fig. 14 is an enlarged end view of a lining form.

Fig. 15 is a top view of the form.

Fig. 16 is a diagram of the main drive mechanism of the machine.

Referring to Fig. 1 of the drawings, the machinery includes a series of hollow blocks 1 fixed between a pair of parallel conveyor chains 2 travelling around sprockets 3. Travel of the conveyor is in the direction indicated by the arrow. A drive shaft 4 rotates continuously but intermittently drives the conveyor through a pitman 5, a notched disc 6 and a pawl 7, Fig. 16.

Lining folding elements arranged to cooperate with the blocks are located along the upper path of the chains. An elevator 8 which raises empty boxes 9 to the path of the blocks for receiving linings is slidably supported at the lower path of the conveyor. A conveyor belt for depositing boxes on the elevator is indicated at 10. Sickle-shaped ejector arms 11 for actuating ejecting mechanism carried within the blocks are located

beyond the elevator and the runway is located at 12 for sliding ejected lined boxes to a delivery belt 13.

A commonly used feed mechanism 14 for the lining material is located at the top of the machine. The lining material is fed from the roll 15 and is cut to suitable lengths before entering the machine by a shearing knife 16 cooperating with the feed mechanism. The drive for the feed mechanism is intermittent in order that the lining material will not be in motion during the shearing process. Feed rollers 17, 18 and 19 guide the lining material to shearing position, from which position the lining is momentarily suspended in the path of the blocks. At the time of the shearing operation one of the moving blocks pushes the severed portion 20 of the lining material between plates 21 located above and below the path of the block, Figs. 2 and 3. The plates force the lining sheet 20 back against the top and bottom of the block, Fig. 4, leaving portions of the lining sheet extending outwardly from each side of the block.

A pair of rotating flap creasing arms 22 at the same moment pass along the sides of the block before arriving in position for the flap creasing operation. During this movement a pair of lining folding arms 23 embrace the sides of the block with an upward movement, Figs. 6, 7 and 8, thereby folding the lower portions of the lining sheet flat against the sides of the block. These actions are so timed that when the arms 23 have completed the upward stroke the flap creasing arms 22 have moved to the position of Fig. 9, thereby producing forwardly disposed flaps 24. Flap bracing extensions 25 of the folding arms 23 are inwardly offset to lie along the inner sides of the flaps, the arms being slotted at 26 to allow this, as shown in Fig. 9.

The folding operation is continued by an upper pair of lining folding arms 27 which descend adjacent the sides of the block, folding the top lining portion over the bottom Fig. 9. Sealing of the bordering lining edges is accomplished by a pair of heaters 28, Figs. 10 and 11 which swing laterally against the lining.

The above operations take place at the top path of the conveyor chains and on their completion the finished lining travels around the sprockets to the bottom where a pair of flap folding fingers 29 (Figs. 12 and 13) cooperate with the movement of the block to fold the forwardly extending lining flaps back against the sides of the lining. These fingers momentarily move inwardly in front of an approaching block, so that

the flaps pass on the outside of the fingers. The fingers immediately move outwardly, thereby bending the flaps, which are folded flat against the box sides by the passage of the block between the fingers.

Insertion of the linings into boxes 9 is accomplished by placing a box on the elevator 8 with the open end of the box toward the approaching block. The hollow block and lining travel into the box, carrying the box from the elevator. After leaving the elevator the lined box is pushed from the block by an ejector mechanism carried within the block and actuated by the ejector arms 11, Fig. 1.

The ejector mechanism, Figs. 14 and 15 comprises a pair of sliding runners 30 held within the block by springs 31. The front ends of the runners are provided with flat heads 32, which abut the inner surface of the lining bottom. Each runner is provided with an inwardly extending lateral projection 33 positioned in the path of the ejector arms. By this arrangement pushing motion of the arms is transferred to the runners which are moved forwardly as indicated by dotted lines in Fig. 15. The lined box is carried from the block by this movement and falls to runway 12 from which the box slides to delivery conveyor 13.

All the elements of the machine are dependent for operation on a connected arrangement of cams and gearing receiving motion from drive shaft 4. This arrangement more or less resembles those commonly used in machines of this general character and is not essential to the improvement; hence, it is not fully illustrated.

Part of the drive arrangement is indicated in Fig. 1 which shows actuating means for the ejector arms and the elevator comprising a pair of cams 34 and 35 fast on the shaft 36 and a pair of springs 37 and 38. The springs pull the ejector arms and the elevator to block engaging position and the cams cause the return strokes. Motion is transmitted from cam 34 to the ejecting arms through a toothed segment 39 pivoted to a shaft 40, the arm 41 of the segment having a roller 42 which bears against the cam 34. In mesh with toothed segment 39 is a similar gear 43 fast to a shaft 44 on which the ejector arms 11 are fixed. An arm 45 for imparting movement from cam 35 to the elevator is pivoted to shaft 40 and linked by a slot and pin connection 46 to the elevator. A roller 47 carried by arm 45 bears against the cam. The cam shaft 36 carries a gear 48 meshing with a gear 49 on the drive shaft 4.

Flap folding fingers 29 are pivoted at 50 (Figs. 12 and 13) to the machine frame and carry rollers 51. Cams 52 and 53 fast to a shaft 54 bear against the rollers and are so shaped that rotation of the shaft causes oscillation of the fingers, as previously described. Shaft 54 is operatively connected to the drive by a sprocket 55 and chain 56 (Fig. 16).

Actuation of the lining folding arms 27 and 23 is accomplished by a cam 57, Fig. 16. The cam bears against a pair of arms 58 and 59 respectively fixed on a pair of shafts 60 and 61 to which are attached the lining folding arms. Connecting means, in this case a gear train 62, lead to the main drive shaft 4 from the cam shaft 63.

Each of the flap creasing arms 22 has a shaft 64 operated by the gear train 62.

The operation of the machine simply involves initially adjusting the lining material in correct shearing position, after which the procedure described above takes place automatically.

We claim:

- 15 1. A machine for forming bag-shaped linings including a form carried by a conveyor, a feed mechanism arranged to deposit a lined sheet in front of the form, lining folding members positioned above and below the path of the form, two 20 pairs of movable folding arms located above and below the path of the form and means for oscillating the arms vertically adjacent the sides of the form, the lower pair of folding arms having inwardly offset forward extensions and slots between the extensions and the folding arms, a pair of flap creasing arms located one adjacent each of the extensions and means for rotating the creasing arms in the direction of travel of the form.
- 20 30 2. A machine for forming bag-shaped linings including a form carried by a conveyor, a feed mechanism arranged to deposit a lining sheet in front of the form, lining folding members positioned above and below the path of the form, two 35 pairs of movable lining folding arms located above and below the path of the form and means for oscillating the arms vertically adjacent the sides of the form, the lower pair of folding arms having inwardly offset forward extensions and slots between the extensions and the folding arms, a pair of flap creasing arms located one adjacent each of the extensions and means for rotating the creasing arms in the direction of travel of the form, a pair of fingers located one at each 40 side of the path of the form and means for oscillating the fingers from the sides to the front of the path of the form.
- 35 45 3. A machine for forming bag-shaped box linings and inserting the linings into boxes including a hollow lining form open at each end and carried by a horizontal conveyor, lining folding elements arranged to form bag-shaped linings around the form with the bottom of the bags across the front of the form, a box supporting elevator arranged to place a box in the path of the form with the open end of the box facing the form and in a position to be entered by the form, and a synchronized drive for the conveyor, lining folding elements and box supporting elevator.
